UNITED STATES PATENT OFFICE.

JOSEPH H. TEMPLIN, OF PHILADELPHIA, PENNSYLVANIA, ASSIGNOR, BY MESNE ASSIGNMENTS, TO GENERAL ELECTRIC COMPANY, A CORPORATION OF NEW YORK.

APPARATUS FOR UNLOADING VACUUM-PUMPS.

1,206,614.

Specification of Letters Patent. Patented Nov. 28, 1916.

Application filed May 31, 1910. Serial No. 564,175.

To all whom it may concern:

Be it known that I, JOSEPH H. TEMPLIN, a citizen of the United States, residing at Philadelphia, in the county of Philadelphia and State of Pennsylvania, have invented a certain new and useful Apparatus for Unloading Vacuum-Pumps, of which the following is a specification.

My invention relates in general to vacuum pumping mechanisms in connection with vacuum-chambers or tanks wherein a predetermined vacuum is desired to be exhausted and when same is attained, to prevent an over-load on the motor which is running continuously and driving the vacuum pump at an approximately constant speed.

It relates more particularly however, to that class of vacuum pumps and tanks or vacuum chambers as commonly used in house-hold or portable vacuum cleaners. It is opposed however to that class of vacuum pumps wherein an enlarged clearance space in the pump-chamber is employed to limit the height of vacuum that the pump can exhaust, as in that construction the pump is designed to suit a predetermined vacuum and is limited to that only; and, it is further opposed to that class of vacuum pumps wherein auxiliary chambers are annexed or connected to the clearance space of the vacuum pump for the purpose of increasing said clearance, and thereby limiting the vacuum to the height desired.

In my invention I require no auxiliary chambers or no extra clearance space in the pump-chamber, as I employ means whereby any desired vacuum may be attained within the range of the vacuum pump as ordinarily constructed and my means can be adjusted and thereby the extreme vacuum limited to any predetermined height desired without overloading the constantly running motor. And, it further relates to novel means I employ whereby the atmospheric pressure coacting with the vacuum attained regulates the loading and unloading of the motor.

Referring to the drawings in which similar letters of reference indicate like parts:— Figure 1 is a sectional view of my preferable design of regulating device, shown in "low pressure" position and installed in a portable vacuum cleaner. Fig. 2 is an en-

larged view of the regulating device, shown 55 in "high vacuum" position.

1 represents a casing with a cover 2, and bottom 3, the whole forming a vacuum chamber 4, hermetically sealed excepting the inlet 5 (which may be adapted to receive the well known suction hose and ren- 60 vater), and the outlet 6 which may be adapted to receive the well known blowing hose.

The pumping mechanism in the structure 65 is comprised of a double acting diaphragm pump frame 7 with the diaphragms 8 and 9 secured to same. Displacing plates 10 and 11 are secured to the central portions of the respective diaphragms. By means of ex- 70 tensions on the edges of the displacers 10 and 11 the said displacers are connected to yoke 12 and by means of the connecting rods 13 they are connected to the crank-pins 14 on cranks 15 which are secured to motor- 75 shaft 16 and driven by motor 17.

By means of the electric plug 18 connection can be made to any ordinary electric light socket and the current conveyed by the cable 19 to the motor 17 causes same to 80 rotate and in turn to reciprocate the displacers and diaphragms, thereby causing an alternate inrush of air through the inlet valves 20 and 21 and a corresponding rush outwardly through the outlet valves 22 and 23 into the passage 24 to the outlet 6 and thence to the free air.

25 is a wall or partition separating the inlet and outlet valve chambers, 26 is an opening in wall 25 and adapted to receive 90 a sliding plunger 27. The central portion of a regulating diaphragm 28 is attached to the end of 27 by means of a screw 29 and washer 30. The outer edge of diaphragm 28 is secured to the wall or partition 25 by 95 means of ring 31 and screws 32 and covers the opening 26 in said wall 25.

33 and 34 are two rollers pivotally supported on lugs 35 and 36 on plunger 27, these rollers are adapted to engage, at the 100 proper times, with the inclines 37 and 38 which depend from their respective inlet valves.

As will be seen plunger 27 is hollow and contains a compression spring 39 therein.

40 is an adjustable plug sliding freely in plunger 27 and is screw threaded at 41, it is also adapted to be adjusted as desired in

the threaded lug 42 which is integral with the pump chamber 7.

From the foregoing description the operation of the machine may be readily understood. Power being applied to the motor, rotation of same causes reciprocation of the diaphragms, the inrush of the air causing the alternate opening and closing of the inlet and outlet valves. When the inlet of the vacuum-chamber or tank is closed or partially closed during the operation of cleaning or from any cause whatsoever the vacuum rises in the vacuum-chamber and a corresponding atmospheric pressure increases on the outlet valves and also on the regulating diaphragm, this pressure on said diaphragm is resisted by the compression spring in the sliding plunger until the vacuum has attained the predetermined height, to which the spring and adjusting plug have been previously "set." The pressure therefore being greater than the spring resistance, the regulating diaphragm and plunger moves forward and the rollers are brought into contact with the inclines on the respective inlet valves, thereby preventing closure of the valves on the return stroke of the diaphragm, thereby permitting the volume of air exhausted from the vacuum chamber by the outward stroke of the diaphragm to be returned to same on the return or inward stroke of the diaphragm. It will be observed that the atmospheric pressure on the outlet valves keeps them closed until the inlet valves are permitted to close by the withdrawal of the plunger upon the lowering of the vacuum in the vacuum chamber or tank. It is also evident that so long as the inlet valves are held open the return stroke of the diaphragm consumes or requires very little or no power as the air withdrawn from the vacuum chamber by the outward strokes of the diaphragm is simply returned to the vacuum chamber in a single acting pump. In a double acting pump some or all of the air may be returned to the opposite end of the pump, the operation being repeated alternately by the pump until the vacuum in the vacuum chamber recedes below the predetermined limit upon which the regulating diaphragm is caused to recede by the pressure of the spring, the inlet valves close and the regular work of pumping the vacuum proceeds.

I am aware of unloading devices in use on compressors and likewise so-called unloading devices in use on vacuum pumps; but I believe I am original in my method of estab-

lishing communication between the pump and vacuum chamber on the return strokes of the displacer and diaphragm at a predetermined vacuum and thereby return the withdrawn air back to the vacuum chamber or to the "out-going" diaphragm or piston.

While I have shown my preferable design, I do not wish to be limited to the particular details in all cases, as changes can be made by those skilled in the art, as, instead of a double diaphragm pump a single acting diaphragm or piston pump may be used, or instead of a regulating diaphragm a piston may be substituted, or an independent communicating passage and valve may be substituted instead of operating the inlet valves, or the atmospheric pressure may be utilized by a device on the exterior of the casing instead of the simple design I have illustrated, which is self contained in the pump *per se*, or various spring devices for regulating the pressure against the atmospheric pressure may be substituted, or in plants where the pump and tanks are separated, the whole regulating device may be located in by-pass pipes connecting the clearances of the vacuum pump with the vacuum tank, any or all of which changes would be within the scope of my method and invention.

Having therefore described my invention, what I claim and for which I desire Letters Patent is as follows:—

In a vacuum creating apparatus, the combination of a casing having a vacuum chamber, a frame therein, a pumping apparatus comprising two parallel opposed diaphragms carried by the frame, a motor, means connecting it to the diaphragms for actuating them, suction and discharge valves for the pumping apparatus, said valves being arranged parallel to each other with the suction valves opposed to each other, a suction and discharge chamber between the valves, a diaphragm separating them, a spring pressed member having a guide adapted to be moved by the diaphragm, rollers on said member, and lugs having beveled faces carried by the suction valves, which lugs are adapted to be engaged by the rollers to lift the suction valves off their seats when the vacuum in the vacuum chamber reaches a predetermined value.

In testimony whereof I affix my signature in presence of two witnesses.

JOSEPH H. TEMPLIN.
